(57) **CLAIM**

The ornamental design for a buckle, as shown and described.

DESCRIPTION

FIG. 1 is a perspective view of the bottom, front and right of a buckle showing my new design;

FIG. 2 is a front view of the buckle;

FIG. 3 is a rear view of the buckle;

FIG. 4 is a top plan view of the buckle;

FIG. 5 is a bottom view of the buckle;

FIG. 6 is a right side view of the buckle, the left side view being mirror image thereof;

FIG. 7 is a cross sectional view of the buckle at 7—7 shown in FIG. 2;

FIG. 8 is a front view of a male body of the buckle;

FIG. 9 is a rear view of the male body of the buckle;

FIG. 10 is a top plan view of the male body of the buckle;

FIG. 11 is a bottom view of the male body of the buckle;

FIG. 12 is a right side view of the male body of the buckle, the left side view being mirror image thereof;

FIG. 13 is a front view of a female body of the buckle;

FIG. 14 is a rear view of the female body of the buckle;

FIG. 15 is a top plan view of the female body of the buckle;

FIG. 16 is a bottom view of the female body of the buckle;

FIG. 17 is a right side view of the female body of the buckle, the left side view being mirror image thereof;

FIG. 18 is a front view of an attaching member of the buckle;

FIG. 19 is a rear view of the attaching member of the buckle;

FIG. 20 is a top plan view of the attaching member of the buckle;

FIG. 21 is a bottom view of the attaching member of the buckle; and,

FIG. 22 is a right side view of the attaching member of the buckle, the left side view being mirror image thereof.
